GOLF PUTTER HEAD

Raymon W. Cook, 1026 Mt. Eden,
San Antonio, Tex. 78213

Filed Dec. 6, 1967, Ser. No. 9,653

Term of patent 14 years

(Cl. D34—5)

FIG. 1

FIG. 2

FIG. 1 is a front elevational view of the golf putter head showing my new design.

FIG. 2 is an end view of the toe thereof.

FIG. 3 is a rear elevational view thereof; and

FIG. 4 is a top plan view of FIG. 3.

I claim:

The ornamental design for a golf putter head, as shown.
